ADVERTISING DEVICE

Thaddeus G. Harrison, St. Paul, Minn.

Application February 14, 1936, Serial No. 63,867

5 Claims. (Cl. 40—28)

The present invention relates to an advertising device, and more particularly to a device which will produce an appearance of change or motion in an aperture in a cardboard folder by means of a transparent strip element, and which will simultaneously project an enclosed card element which may also be used to produce an illusion in said aperture.

Various types of card devices have been made which produce an illusion of movement or change in characters imprinted thereon, but in none of these so far as is known at the present time, is there incorporated the novel features of construction and operation embodied in the present invention.

An object of the present invention is to make an improved novelty card device.

Another object is to make a card device having an aperture therein and of producing an appearance of movement or change in said aperture by means of a transparent strip movable with respect to said aperture and having designs or characters carried by said strip and movable into or out of registry with said aperture upon movement of said strip.

Another object of the invention is to make a card device having an aperture therein and having a transparent strip folded into said card device and movable with respect to said aperture, said strip having designs or characters thereon movable into and out of registry with said aperture upon movement of said strip, and a card element positioned in a fold of said strip to be projected by a movement of said strip.

In order to attain these objects, there is provided, in accordance with one feature of the invention, a folded cardboard cover having an aperture in an exposed face thereof, and having a strip of "Cellophane" folded into the cover member to have a portion thereof exposed through the aperture in the cover. The aperture in the cover is preferably a cut-out portion of a representation printed on the cover. The "Cellophane" strip, which is transparent, has imprinted or otherwise suitably affixed thereon opaque portions designed to pass the aperture on the cover when the strip is moved to give the impression of movement or change in the portion of the representation on the cover within the aperture. If desired, the cover portion back of said aperture can also have imprinted or otherwise suitably affixed thereto a representation adapted to co-ordinate with the representation on the cover. A card, separate from the cover, is inserted in a fold of the "Cellophane" so

as to be projected from the cover upon withdrawing the "Cellophane" strip, and may also have a portion thereof adapted to move across the cover aperture to produce an illusion.

These and other features of the invention will be more fully set forth in the following description and the accompanying drawings, wherein:

Figure 1 is a view in perspective of a cover folder and associated parts in normal position.

Figure 2 is a front view of the device shown in Figure 1 with a "Cellophane" strip partially withdrawn and with a contained card partially projected from the cover folder.

Figure 3 is a view in perspective of a "Cellophane" sheet embodied in the constructions shown in Figures 1 and 2.

Figure 4 is a sectional view on the line 4—4 of Figure 1.

Figure 5 is an end view of the cover folder alone showing a method of folding.

Figure 6 is a cover blank for the device shown in Figures 1 and 2 in reduced scale, the lines of fold being indicated by dotted lines.

Figure 7 shows a modified form of the invention in normal condition, a portion of the cover of the folder being broken away.

Figure 8 is a view of the device shown in Figure 6 in partly operated condition.

Figure 9 is a front view in reduced scale of the cover blank employed in the device illustrated in Figures 6 and 7, the lines of fold being indicated in dotted lines.

Figure 10 is a view in perspective of the "Cellophane" strip employed in the device illustrated in Figures 6 and 7; and

Figure 11 is a front view of a card adapted to be inserted in the folder to lie in a fold of the "Cellophane".

Referring to the drawings in detail, and considering first the structure shown in Figures 1 to 4, inclusive, of the drawings, a folder blank 1 is prepared, as shown in Figure 6. The dotted lines, indicating the lines of fold, divide the blank into four substantially equal areas numbered 2, 3, 4, and 5, respectively. The portion 3 has imprinted thereon a picture of the head and shoulders of a youth 6, with the face portion cut out to leave an aperture 7. A notch 9 is provided in the lower edge of the portion 3 to facilitate grasping a tab on a "Cellophane" strip to be later described in detail. On the back of the portion 2, and positioned to register with the aperture 7 when the portion 2 is folded backwardly and against the rear face of the portion 3, is imprinted the face 8 of the youth 6.

A "Cellophane" strip 10 is provided of a length to approximately three times the width of the blank 1, and of a width to be freely slideable within the folder when folded as shown in Figures 1, 2, 5 and 5. A tab 11, which may be of paper, is adhesively secured to one end of the strip 10, and the other end of the strip 10 is adhesively secured to the upper end of the inner (as it appears in Figure 5) side of the portion 4. A card 12, see Figure 10 11, is of about the same length as the width of the blank 1, but is of a width to slide freely in the folder when folded. The card 12 is positioned in front (as seen in Figure 3) of a portion 10a of the strip 10 and the strip is folded as at 10b around 15 the lower edge of the card 12. The portion 2 of the cover is folded against the rear face of the portion 3, with the portion 10c of the strip 10 therebetween, with the spotted portion 13 of the strip 10 overlying the face 8 of the youth which appears 20 through the aperture 7 when thus folded. The portion 4 is then folded rearwardly to lie rearwardly of the portion 2, and the strip 10 and the folded portions 10a and 10c with the contained card 12, is positioned between the portions 2 and 25 4 of the cover. When thus folded the tab 11 lies in the notch 9, and the device appears as in Figure 1, and the cover is glued as along the edge 13a to secure the parts in assembled position. The pink spots 13 are imprinted or otherwise applied 30 to the strip 10 in a position to register with the aperture 7 when the strip is assembled as in Figures 1, 2, and 4, and to overlie the face 8 printed on the portion 2. When thus assembled, as shown in Figure 1, these dots have the appearance of 35 pimples or blotches on the youth's face.

To operate the device the sides of the cover folder are grasped by one hand and the tab 11 is grasped between the thumb and forefinger of the other hand and is pulled downwardly, as shown in 40 Figure 2. This motion moves the spots 13 out of registry with the opening 7 leaving only the clear "Cellophane" overlying the face 8 of the youth, as shown in Figure 2. As the strip 10 is drawn downwardly, as illustrated in Figure 2, the fold of 45 the "Cellophane" strip comprising the portions 10a and 10c is shortened, thereby projecting the card 12, which has its lower edge resting in the fold upwardly, as shown in Figure 2. This card may bear an appropriate message of a type which 50 can be read line by line, or may be in the form of a postal card which can be filled out by the recipient and returned to the sender, as is desired in many types of advertising campaigns.

The modified device shown in Figures 7, 8, 9, 10, 55 and 11 is of a type suitable for a beverage advertisement or greeting card. In this construction a blank 20, see Figure 9, is provided with three vertical creases to divide the card into four areas 21, 22, 23, and 24. In the area 23 a picture of a hand 25 is depicted as grasping a bottle 26, the portion of the bottle above and below the hand being cut away to leave an opening surrounded by the outline depicting the bottle. This opening is extended downwardly, as at 27, and the outline of a 60 glass 28 is imprinted, the interior of the glass being cut away to form an enlarged extension of the opening 27. In the portion 24 an opening 29 is cut in a position to register with the opening 28 when the portion 24 is folded rearwardly to 65 overlie the rear face of the portion 23. On the rear face of the rear portion 22, as illustrated in Figure 9, is imprinted an area 30 to register with the opening 28 when folded, the color of this area being the color of the liquid which it is desired to 70 simulate being poured into the glass. After the 75

portion 24 is folded over rearwardly to overlie the portion 23, the portion 22 is also folded over rearwardly to overlie the portion 24, the portion 21 extending outwardly to the right, as a cover flap.

A "Cellophane" strip 31 comprises three portions 32a, 33a, and 34a, folded in the same manner as the strip 10 illustrated in Figure 3. A portion 35 of the strip is colored the same color as the area 30 and is preferably also imprinted with a series of small circles which represent bubbles, as 10 the liquid rises in the glass. This portion 35 is positioned on the strip 31 so that when the "Cellophane" strip is inserted in the folder, as illustrated in Figure 4, with a card 12 inserted in the rear fold 36, the upper end of the colored portion 15 35 on the portion 33 of the "Cellophane" strip will be below the bottom of the opening 28, so as not to be visible through this opening. A portion 37 on the forward fold 34 of the "Cellophane" strip is also colored the same color as the area 30 on the 20 folder and the left hand portion of this area is preferably provided with small circles to indicate bubbles as the liquid is poured from the bottle. The lower end of this area 37 is preferably the 25 height to register with the lower end of the cut-out portion 27 when the parts are in normal position, as indicated in Figure 7. With the parts in this normal position indicated in Figure 7 the portion 37 will substantially fill the entire cut-out portion within the outline of the bottle 26 and 30 extend to the lower end of the cut-out portion 27. The strip 31 is provided with reinforced end portion 38 to facilitate manipulation.

To operate the device the sides of the folder are grasped between the thumb and fingers of 35 one hand and the tab 38 is grasped by the other hand and pulled downwardly. This draws the portion 34 of the "Cellophane" strip downwardly giving the appearance of liquid flowing downwardly into the glass. The parts are arranged 40 so that as the portion 37 reaches the bottom of the glass the upper edge of the colored portion 35 will simultaneously reach the bottom of the cut-out portion 28 of the glass, and the liquid will thus appear to rise in the glass as it goes down 45 in the bottle, giving the illusion of pouring liquid from the bottle into the glass. As this progresses the card 12 will be ejected upwardly by the shortening of the fold of the rear portions of the "Cellophane" strip, and when the bottom of the card 50 is drawn upwardly to clear the upper edge of the glass, the colored portion 30 on the portion 22 of the folder will then be visible through the 55 openings 28 and 29 to give the appearance of a filled glass of liquid.

The two embodiments illustrated and described are sufficient to permit one skilled in the art to work out an endless variety of designs and actions by suitably arranging cut-out areas within various types of printed representations on the various 60 folds of the folder and co-operating colored areas on the "Cellophane" strip, together with openings to be cleared by the lower edge of the card, as the card 12 is projected upwardly. The fact that the card is projected upwardly at one-half 65 the rate of speed with which the operating tab 38 in Figure 7, or 11 in Figure 1, permits this factor to be utilized as a speed variable where this is desired in the illusion. The device is simple of manufacture and capable of a wide field of use 70 as an advertising or greeting card, and provides the desirable feature of placing a secondary message in the card as it is projected, and which is capable of remailing to the sender, the card being projected in such a way that it is impossible 75

for the recipient after operating the device to overlook the card.

I claim:

- 5 1. A novelty device comprising a folded body portion having a cut-out opening in an exposed face thereof, a representation imprinted around such opening to incorporate such opening as a portion of such representation, a secondary representation interiorly of said device positioned to 10 co-operate with said opening, a transparent, flexible strip member folded within said folder, and a card inserted in a fold of said transparent, a flexible strip, one end of said strip being positioned to be grasped by an operator and the 15 other end of said strip being secured to said folder to project said card from said folder on a withdrawal of said strip and to simultaneously produce an illusive effect within said opening.
2. A novelty device comprising a folded body portion having a representation on the front thereof and having a co-ordinated cut-out opening therein, a representation on an inner portion of said folded body portion registering with said opening to be visible therethrough, and a 25 transparent strip having a representation thereon to be displayed through said opening, said strip being adapted to be withdrawn to move said representation thereon across said opening to produce an illusive effect in said opening.
- 30 3. A novelty device comprising a folded body portion having an exposed representation thereon and having a co-ordinated cut-out opening therein, a representation on an inner portion of said folded body portion registering with said opening to be visible therethrough, a transparent strip 35 folded between successive layers of said body por-

tion and having one end of said strip secured to said body portion and the other end of said strip exposed, and a card inserted in a fold of said transparent strip to be projected by drawing outwardly the exposed end of said strip.

4. A novelty device comprising a plurality of layers of superposed sheet material, a representation on an exposed layer of said device, said layer having a co-ordinated cut-out opening therein, a folded, transparent strip inserted between successive layers of said device and having an end thereof secured against movement and having an opposite end thereof exposed, and a card inserted in a fold of said strip to be wholly contained within said device, a withdrawal of the exposed end 15 of said strip projecting said card outwardly from said device to be visible through said opening to produce an illusion in passing said opening.

5. A novelty device comprising a body portion having a plurality of superposed layers of material, a representation on an exposed face of one of said layers and having a co-ordinated opening therein a double folded, transparent strip having a card inserted in one fold thereof to be wholly contained between two rearward layers 25 of said device, and having a second fold thereof pass between two outer layers of said device, one end of said transparent strip being secured to said device and the other end of said strip being exposed, said strip carrying a representation positioned to pass said opening during a withdrawal of said strip to produce an illusion within said opening, the withdrawal of said strip by means of said exposed end projecting said card outwardly from said device.

THADDEUS G. HARRISON.
